UNITED STATES PATENT OFFICE

MAX BOCK, OF BAD KISSINGEN, GERMANY

MEANS FOR PROTECTING WOODEN MASTS, POLES, SLEEPERS, AND THE LIKE

Application filed February 9, 1928, Serial No. 253,039, and in Germany April 6, 1928.

I have filed applications in Germany, on the 6th of April, 1926; in Great Britain, on the 20th of September, 1927 of which the following is a specification.

5 My invention relates to the impregnation of wooden masts, poles, sleepers and the like, and has for an object to provide simple and inexpensive means which permit automatic and local impregnation even in the case of 10 masts, poles and the like already erected and in use.

The drum impregnation processes and immersion processes heretofore commonly in use are costly on account of the necessity for 15 employment of expensive mechanical contrivances and are open to the objection that the wood cannot be impregnated in situ. Further, they are open to the objection that the wood cannot be so impregnated as to take 20 account of the non-uniformity of the action of the weather over the entire length of the wooden members. As is found by experience in wood exposed to weather influences rot makes its appearance at different points

25 to quite unequal extents. For example, in upright poles rot occurs directly above and beneath the surface of the ground, as well as at the top and at places where, by reason of the form of the pole surface or of the presence 30 of attachments, a stream of rain water flowing over the pole surface is liable to be suddenly arrested and dammed up more than at other points, so that at these points the media which cause rot have sufficient time to 35 penetrate through the air gaps into the wood. From these points rot extends slowly in all directions.

There are already known devices for effecting the automatic and local impregnation 40 of masts and the like. In general the devices employed comprise rings formed as containers which are fixed to the wood at the exposed points and mate with the surface of the wood to be protected, forming therewith enclosed chambers which are filled 45 with an antiseptic liquid which is free to penetrate air gaps and artificially formed incisions in the wood. In the use of these devices it is found difficult to secure the containers tightly enough to the surface of the

wood. Further, it is necessary to refill the containers from time to time as the impregnating medium must be very fluent, so that it can penetrate the wood, and is usually feeble in its action.

55 The above drawbacks are overcome by my invention in respect that the container serving for reception of the impregnating medium is formed of material penetrable by moisture so that impregnating media in concentrated, preferably solid or powder form can be used, being capable of taking up rain water or the like to form a solution that penetrates the wood. In order that the impregnating medium may not collect at the lowest 60 part of the container, but that the solution may penetrate the wood uniformly over the entire area of the container, such container is formed of two or more plies of a material or fabric which is both pliable and penetrable by moisture, the plies being jointed together by stitching or the like to form a 65 number of spaced pockets or compartments containing the impregnating medium.

70 It will be evident that the container proposed to be used far excels in cheapness and effectiveness all containers heretofore used, and that, as it preferably consists of pliable material, it can be nailed to the wood at any desired point and requires no attention whatever.

75 In the accompanying drawing are illustrated, by way of example, embodiments of my invention.

80 Fig. 1 shows a wooden post which carries at its upper end and at a channel secured thereto containers for impregnating medium.

85 Fig. 2 shows a wooden mast or post to which an annular container for impregnating medium is fixed directly beneath the ground level.

90 Figs. 3 and 4 are respectively a plan and a cross-section of a railway sleeper to which is attached a strip-like carrier for impregnating medium.

95 Fig. 5 is a section of a beam embedded in masonry which is provided with containers for impregnating medium at its encastré end and on its end face.

100 Figs. 6 and 7 show in developed plan and

longitudinal section respectively, a container for impregnating medium.

To the pole *a* (Fig. 1) at the upper end or crown of inverted V form there is secured by straps *b* fixed by nails *b*¹ to the pole *a* a purse-like container *c* for impregnating medium having an annular ledge *c*¹ presenting a cup for taking up rain water. The solution of the medium in rain water penetrates between the rings of the wood downwardly into the pole. By means of the channel member *d* secured to the pole there is also clamped to the mast a second container *e* so that rain water dammed by the channel member penetrates the container and forms with the medium therein an active solution.

The annular container *f* (Fig. 2) is secured to the mast or post immediately beneath the surface of the ground. The solution formed by the action of ground moisture and rain water on the medium penetrates the mast radially and gradually passes downwardly and upwardly, more upwardly than downwardly because of the capillary action. Because of this last named action the container may be disposed slightly beneath the surface. The container is formed as a plurality of connected pockets effected by stitching as indicated at *h*.

30 The railway sleeper *i* (Figs. 3 and 4) carries on its upper face a strip-like container *k* secured by spikes *k*¹ or the like to the sleeper and covering the major part of the surface, so that the solution or extract formed by the 35 action of rain water distributed uniformly over the surface penetrates downwardly into the sleeper.

The beam 1 embedded in masonry is wrapped bandage fashion by a container *m* 40 at its encastré end. To its end face is also attached a container *n* of a form matching the cross-sectional contour of the beam.

The container shown in Figs. 6 and 7 consists of two plies *r*, *s*, of fabric penetrable by 45 moisture between which plies is interposed impregnating medium in powder or solid form. By means of longitudinal seams *p*¹ and transversed seams *p*² the container is divided into a large number of separate compartments or pockets *c* so that the impregnating medium with which the container is charged is uniformly distributed and does not collect at the lowest point.

55 What I claim as my invention and desire to secure by Letters Patent of the United States is:—

1. Means for protecting wooden masts, poles, sleepers and the like, comprising a container adapted to fit the top of such poles or masts and to be secured thereto beneath the surface of the ground, comprising two plies of moisture absorbing material joined together to form a plurality of separate compartments adapted to contain an impregnat-

ing medium soluble under the influence of moisture.

2. The invention according to claim 1, in which the container for the top of a pole is of purse-like formation to contain the impregnating medium and is provided with a cup-shaped ledge for conveying rainwater to said medium.

3. The invention according to claim 1, in which an auxiliary container is associated with the main container and adapted to be clamped to the pole.

MAX BOCK.
